UNITED STATES PATENT OFFICE.

EDWIN E. SLICK, OF WESTMONT BOROUGH, PENNSYLVANIA.

WATER-COOLED PORT.

1,322,837.

Specification of Letters Patent. Patented Nov. 25, 1919.

Application filed September 2, 1916. Serial No. 118,307.

To all whom it may concern:

Be it known that I, EDWIN E. SLICK, a citizen of the United States, residing in the borough of Westmont, in the county of Cambria and State of Pennsylvania, (whose post-office address is Johnstown, Pennsylvania,) have invented certain new and useful Improvements in Water-Cooled Ports; and I do hereby declare the following to be a full, clear, and exact description, such as will enable others skilled in the art to which it appertains to make and use the same.

My invention relates particularly to a water-cooled port for open hearth or other furnaces and consists of a series of pipes inclosed in a metallic casting which extends through the inner or hearth end of the arch separating the gas port from the air port.

One of the objects of my invention is to provide, at the points where the gas and air ports unite, a cooling apparatus that will absorb the excessive heat necessary in open hearth and similar furnaces, and thereby prevent the separating arch between the gas and air ports from being destroyed by the action of the high temperatures.

Another object of my invention is to so construct such apparatus that the cooling pipes will not be in direct communication with the burning gases; but inclosed in a metal casting or casing that will form part of the top surface of the gas port and of sufficient thickness to carry off the excessive heat uniformly.

A further object is to so place this cooling casting that it will reinforce and support the inner end of the arch separating the gas and air port and thereby prevent the ends of the said arch from chipping off or falling, if partially destroyed or broken by the heat.

Certain other objects of my invention will be apparent from the description and claims hereinafter set forth in that it may be simply and economically constructed, practical to operate and free from complications that would require frequent repairs.

Referring now to the accompanying drawings in which like letters of reference designate corresponding parts:—Figure 1 is a cross sectional elevation of an open hearth furnace on the line I—I of Fig. 3 showing my invention applied thereto; Fig. 2 is a cross sectional elevation of the same furnace taken through the center thereof; Fig. 3 is a sectional view taken on the broken line III—III of Fig. 1; Fig. 4 is a plan view of

my cooling casting and pipes; Fig. 5 is a side elevation of the casting and pipes shown in Fig. 4 and Fig. 6 is a sectional end elevation of the casting and pipes shown in Figs. 4 and 5.

The air port 1 and the gas port 2 are inclined at the proper angle to cause intensely hot sheets of burning gases to be evenly distributed over the charge contained in the oval-shaped hearth 3, and being thus conducted in a downwardly direction, the burning gases will not be projected against the bricks of the roof 4 and of the side walls 5 above the slag line thereof, thereby preventing the melting or destruction of this brick or refractory material.

The flues 6 and 7 connect respectively the air and gas ports 1 and 2 with the regenerative chambers and said flues are adapted to either admit regenerated air and gas or to conduct the outgoing burnt gases to the regenerators whence they are conducted to the chimney.

When the air and gas is admitted through the flues 6 and 7 and the ports 1 and 2, they will be united at the inner end of the separating arch 8, thereby producing an intense heat that will be transmitted to the end of said arch 8. When the air and gas are being admitted at corresponding ports at the other end of the furnace, the arch 8 will be subject to a still greater heat, for in this case the intensely heated portions of the outgoing gases will be in direct communication with the end of the arch.

In order to protect the end of arch 8 from this intense heat, cooling pipes 9, inclosed at their central portions in a casting 10, are built into the underside of the separating arch 8 at the end portion thereof. A portion of the underside of the casting 10 lies in the direct continuation of the under surface of the separating arch 8 and said casting does not project into the gas port 2. A free uninterrupted passage of the gas along port 2 is thereby permitted with the cooling casting so placed. Water or other cooling fluid is supplied to the pipes 9 through the inlet connections 11, flows inwardly and through the casting 10 absorbing the excess heat, thereby preventing the temperature of the materials of construction of the separating arch 8 from rising to a point that would burn them away. The fluid, after absorbing a certain amount of heat, will be carried off through the dis-

charge connections 12 to boilers or to other places where preheated fluid may be desired, or it may be wasted if preferred.

The casting 10 which is shown in Figs. 5, 4, 5 and 6, protects the water pipes 9 from the direct actions of the hot flames and not only prevents the said pipes from being burnt away, but also provides a greater cooling surface at points where the heat is most intense. This casting forms the roof of the outlet end of the gas port and the flat arch slope, as shown in Fig. 5, causes the gas to be discharged in a flat sheet over the charge of the furnace.

15 It should be noted that the casting 10, in addition to being slightly arched over the port, has flat bearing ends, which are adapted to rest upon and be supported by the brick work, the shape of these flat ends being substantially that of a brick, so that the metallic arch does not disarrange the brick courses. It should also be noted that the use of a number of pipes of small diameters within the flat arch provides a 25 thorough circulation of cooling water at all times within the casting; whereas in other and box-like constructions there is no water circulation in certain localities, so that gas, steam or air accumulates and due 30 to the absence of cooling fluid these constructions are burned and spoiled, all of which is obviated by my plurality of small conduits of small size, each supplied with large quantities of moving water and discharged under considerable pressures.

Although I have shown and described my invention in considerable detail, I do not wish to be limited to the exact construction shown and described, but may use such substitutions, modifications, or equivalents

thereof, as are embraced within the scope of my invention, or as pointed out in the claims.

Having thus described my invention, what I claim and desire to secure by Letters Patent is:—

1. In a furnace an air port and a gas port arranged one above the other and each downwardly inclined toward the hearth of the furnace, a separating arch intermediate the air port and the gas port, cooling pipes extending transversely through the furnace near the outlets of said ports, an arched metallic casing with flat bearing ends extending below and adapted to support the 50 said separating arch and inclosing the said cooling pipes, each pipe connected to a source of fluid supply.

2. In a furnace an air port and a gas port, a separating arch intermediate the 60 said ports, an arched metallic casing with flat ends forming the lower portion of the inner end of the separating arch, a plurality of water cooled pipes extending transversely through the furnace and through the said 65 casting, each pipe connected to a source of fluid supply.

3. In a furnace an air port and a gas port arranged one above the other at each end of the furnace, a separating arch intermediate 70 each pair of said ports, an arched metallic casing with flat ends extending through the end of each separating arch and a plurality of water cooled pipes extending transversely through the furnace and through 75 the casing, each pipe connected to a source of fluid supply.

In testimony whereof, I have herewith set my hand.

EDWIN E. SLICK.
